CLAIM

The ornamental design for a bottle, as shown and described.

DESCRIPTION

FIG. 1 is a top perspective view of a first embodiment of a bottle;

FIG. 2 is a front view of the bottle shown in FIG. 1;

FIG. 3 is a back view of the bottle shown in FIG. 1;

FIG. 4 is a right side view of the bottle shown in FIG. 1;

FIG. 5 is a left side view of the bottle shown in FIG. 1;

FIG. 6 is a top view of the bottle shown in FIG. 1;

FIG. 7 is a bottom view of the bottle shown in FIG. 1;

FIG. 8 is a perspective view of a second embodiment of a bottle;

FIG. 9 is a front view of the bottle shown in FIG. 8;

FIG. 10 is a back view of the bottle shown in FIG. 8;

FIG. 11 is a right side view of the bottle shown in FIG. 8;

FIG. 12 is a left side view of the bottle of FIG. 8; and,

FIG. 13 is a top view of the bottle of FIG. 8.

The dashed lines in FIGS. 1 to 13 represent environmental structure and form no part of the claimed design. All other surfaces or portions of the bottle not shown in the figures or otherwise described in the specification form no part of the claimed design.
